COLLAPSIBLE SWING SEAT

Carroll L. Pierce, Cleveland, Ohio

Application September 21, 1955, Serial No. 38,025

Term of patent 3½ years

(Cl. D15—11)

Fig. 1 is a perspective view of the collapsible swing seat taken from a point near the front left corner and slightly above.

Fig. 2 is a perspective view of the collapsible swing seat taken from a point near the rear right corner and slightly above.

Fig. 3 is a perspective view of the collapsible swing seat taken from the same point as Fig. 1, but showing the swing seat in collapsed condition.

I claim:

The ornamental design for a collapsible swing seat, as shown.
